HANDLE UNIT

Kurt Burgold, Asheville, N. C., assignor to Morgan Furniture Company, a corporation of Delaware

Application June 24, 1948, Serial No. 147,157

Term of patent 3½ years

(Cl. D10—8)

To all whom it may concern:

Be it known that I, Kurt Burgold, a citizen of the United States, residing at Asheville, in the county of Buncombe and State of North Carolina, have invented a new, original, and ornamental Design for Handle Unit, of which the following is a specification, reference being had to the accompanying drawing, forming part thereof.

Fig. 1 is a front view of a handle unit, showing my new design;

Fig. 2 is an end view of the same;

Fig. 3 is a top plan view thereof;

Fig. 4 is a bottom plan view thereof;

Fig. 5 is an enlarged end view; and

Fig. 6 is an enlarged front view.

The dotted line showing of Figs. 1 and 2 is for illustrative purposes only.

I claim:

The ornamental design for a handle unit, as shown and described.

KURT BURGOLD.
